H. DUCA.
ANCHORING DEVICE.
APPLICATION FILED MAY 10, 1920.

1,358,715.

Patented Nov. 16, 1920.

UNITED STATES PATENT OFFICE.

HENRY DUCA, OF WILSON, MICHIGAN.

ANCHORING DEVICE.

1,358,715.

Specification of Letters Patent. Patented Nov. 16, 1920.

Application filed May 10, 1920. Serial No. 380,407.

To all whom it may concern:

Be it known that I, HENRY DUCA, a citizen of the United States, residing at Wilson, in the county of Menominee and State of Michigan, have invented certain new and useful Improvements in Anchoring Devices, of which the following is a specification, reference being had to the accompanying drawings.

10 This invention relates to improvements in anchoring devices for a check row line, and it is an object of the invention to provide a novel and improved device of this general character embodying means whereby one 15 end portion of the line may be automatically shifted from one point in the field to another and which shifting operation is under control of the check line.

It is another object of the invention to 20 provide an anchor of this general character embodying novel and improved means whereby the end of the line connected to the anchor may be raised to different heights as the result of a manipulation of the check 25 line.

The invention consists in the details of construction and in the combination and arrangement of the several parts of my improved device whereby certain important 30 advantages are attained and the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:

40 Figure 1 is a view in top plan, illustrating an anchoring device for a check row line constructed in accordance with an embodiment of my invention;

Fig. 2 is a view in front elevation of the 45 device as illustrated in Fig. 1;

Fig. 3 is a sectional view taken substantially on the line 3-3 of Fig. 1; and

Fig. 4 is a view in end elevation of my improved attachment as herein embodied, 50 certain of the parts being omitted for clarity in disclosure.

As disclosed in the accompanying drawings, 1 denotes an elongated member provided at its opposite end portions with the 55 perpendicularly related prongs 2 adapted

to penetrate the ground when the anchor is in applied position. The central portion of the member 1 has extending forwardly therefrom and substantially at right angles thereto a short arm 3 terminating in its 60 outer or free end in a depending prong 4 which is also adapted to penetrate the ground when the anchor is in working position. Mounted upon the outer end portion of the arm 3 is a bracket 5 which supports 65 a spool or drum 6 upon which the check row line 7 is adapted to be wound.

Mounted upon the inner portion of the arm 3 for rotary movement therearound is a sleeve 8 carried by an end portion of an 70 elongated arm 9. The outer or free end portion of the arm 9 terminates in an angularly disposed prong 10 which, when the arm 9 is in one position, also penetrates the ground. Secured to one of the prongs 2 75 is a locking or holding device L and, as herein disclosed, said device comprising a substantially U-shaped member 11 having one of its side arms 11^a secured to the prong 2. The locking device L extends forwardly 80 of the prong or is so arranged that the arms 11^a of the member 11 and the coacting prong 2 are arranged in substantially the same vertical plane. The arm 11^a of the member 11 connected to the prong 2 is provided with a 85 plurality of longitudinally spaced lugs 12, preferably three in number with the lowermost prong spaced above the base portion of the member 11. The second or outer arm 11^a is provided with the inwardly directed lugs 14 positioned substantially midway of the lugs 12.

15 denotes a bow spring having one end portion secured to and coiled about the inner portion of the arm 3 with the opposite 90 end portion of said spring secured to the arm 9 and which spring serves automatically to throw the arm 9 from one position to another when said arm is disengaged from the locking or holding device L. 100

Mounted upon the arm 9 and adjustable longitudinally thereof is a collar 16 provided with a forwardly directed eye member 17. The check line 7 extends from the spool or drum 6 rearwardly through a guide member 18 carried by the inner portion of the arm 3 and from that point continues laterally and through the eye member 17. From this point the wire is adapted to be properly disposed across the field. By having 110

the collar 16 adjustable along the arm 9, the position of said collar 16 may be adjusted with respect to the arm 3 so that the proper spacing of the rows may be provided for.

5 In practice, after an anchoring device has been positioned at one end of the field, the arm 9 is swung into a position to be held by the lower lug 12 against upward movement under the influence of the spring 15
10 and when in this position, the prong 10 at the outer or free end of the arm 9 is upwardly directed. The check line 7 coacts with the planter in a well known manner and should it be of advantage to raise the
15 anchored end of the line when the planter is in the middle portion of the field, it is only necessary to impose pull upon the check line. This pull will free the arm 9 from the lowermost lug 12 whereupon the
20 spring 15 will cause the arm to raise upwardly into contact with the lower lug 14 which lug causes the arm 9 to engage below the intermediate lug 12. A second pull will cause the arm 9 to disengage from the intermediate lug 12 and engage, through the instrumentality of the upper lug 14, the
25 top lug 12. In the present embodiment of my invention, the arm 9 serves to hold the anchored end of the check line 7 at three
30 different points of elevation.

When the end of the line is reached and it is desired to throw the line over to a second point on the field, it is only necessary for the operator to impose a sufficient number of pulls on the check line 7 to free the same from the locking device L and whereupon the spring 15 will automatically throw the arm 9 over to the opposite side of the arm 3. By this means, the necessity of the
35 operator going back to re-set the line is eliminated. Should the arm 9 be engaged with the lowermost lug 12, a complete release of the arm 9 is accomplished by three pulls imposed upon the line 7 and so on.

40 45 In practice, it is preferred that two of my improved devices be employed substantially duplicate in construction except that initially the arm 9 of one device is disposed to the right and the arm of the second device is initially disposed to the left. By this arrangement the proper shifting of the check lines may be conveniently effected.

From the foregoing description, it is thought to be obvious that an anchoring device constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement
50 55 60 65 and formation of the several parts herein

shown in carrying out my invention in practice except as hereinafter claimed.

I claim:—

1. A check row anchor comprising an elongated member provided with penetrating means, an arm supported by said member for upward swinging movement in a direction longitudinally of said member, said arm being provided with penetrating means, a locking device carried by the elongated member and coacting with the arm when said arm is in one position, said arm being vertically adjustable within said locking device and means for automatically swinging the arm when released from the locking device. 70 75 80

2. A check row anchor comprising an elongated member provided with penetrating means, an arm supported by said member for upward swinging movement in a direction longitudinally of said member, said arm being provided with penetrating means, a locking device carried by the elongated member and coacting with the arm when said arm is in one position, and means for automatically swinging the arm when released from the locking device, said locking device constituting a pair of substantially parallel arms each provided with a plurality of inwardly directed lugs positioned in staggered relation. 85 90 95

3. An anchor of the class described comprising an elongated member provided with penetrating prongs at its opposite end portions, a laterally disposed arm secured to the central portion of the elongated member and provided with penetrating means, an arm having one end portion fulcrumed to the first named arm whereby said second named arm has upward swinging movement 100 105 in a direction longitudinally of the elongated member, the opposite end portion of said second named arm being provided with a prong, a locking device carried by one end portion of the elongated member and with which the second named arm engages, said arm being vertically adjustable within said locking device the penetrating member of the second named arm being upwardly disposed when said second named arm is engaged with the locking device, automatic means to swing the arm when released from the locking device, and a check row line engaged with the second named arm, said check row line constituting a means for adjustably elevating said second named arm within said locking device and releasing the second named arm therefrom. 110 115 120

4. The combination with a check wire of means controlled by said wire for automatically shifting one end of said wire from one point in the field to another and means likewise controlled by said wire for adjustably elevating said end. 125

5. The combination with a check line of 130

means for adjustably elevating one end of said line, means for automatically shifting said end of the line from one point in the field to another and means remote from said 5 end of the line for controlling said elevating and shifting means.

6. A check wire attachment comprising a rod having means for fastening it in a horizontal position on the ground, an arm pivotally connected with said rod to swing from 10

one end to the other thereof, means for normally locking said arm on one end of said rod, means for adjustably elevating said arm within said locking means and means for releasing said arm from said locking means 15 to allow said arms to swing to the other end of said rod.

In testimony whereof I hereunto affix my signature.

HENRY DUCA.
